UNITED STATES PATENT OFFICE.

ZEDDIE LEE HARBIN, OF EAST GASTONIA, NORTH CAROLINA, ASSIGNOR OF ONE-HALF
TO EMANUEL FROHMAN, OF EAST GASTONIA, NORTH CAROLINA.

TENSIONING DEVICE.

Application filed September 20, 1926. Serial No. 136,675.

This invention comprehends the provision of a device for tensioning thread, worsted or the like as it is taken from a ball, skein or bobbin, irrespective of the size and shape 5 of the latter, the thread leaving the bobbin or the like in a free and unobstructed manner.

An object of the invention resides in the provision of means for adjustably supporting the tensioning device, together with means for supporting the bobbin at any desired distance from the tensioning device, so that the thread can be freely taken from the bobbin.

Another object of importance resides in the provision of means for preventing whipping of the thread as it passes through the device, and to assist in guiding the thread beneath the tensioning element of the device.

More specifically stated the invention embodies a channel-like member through which the thread passes as it leaves the bobbin or the like, and beneath a tensioning element arranged at one end of the member and susceptible of adjustment whereby the tension 25 on the thread or the like can be regulated.

A further object of the invention resides in the provision of a pivotally mounted weighted element normally seated in the channel-like member directly in advance of the tensioning member, to assist in guiding the thread beneath the tensioning element, and at the same time prevent whipping of the thread as it passes through the member.

In carrying out the invention I also contemplate the provision of means whereby the pivoted weighted element can be adjusted with relation to the channel-like member so as to be properly positioned with relation to the thread, worsted or the like with which it is used.

A still further object of the invention resides in providing the channel-like member with an opening in the bottom thereof arranged directly beneath the weighted member, so that any lint or other material that might accumulate beneath the weighted member, can readily find its way through the opening to avoid clogging or obstructing the channel-like member.

The nature and advantages of the invention will be better understood when the following detail description is read in connection with the accompanying drawings, the invention residing in the construction,

combination and arrangement of parts as claimed.

In the drawings forming part of this application like numerals of reference indicate similar parts in the several views and 60 wherein:

Figure 1 is a view in elevation of the invention.

Figure 2 is a fragmentary view looking at the opposite side of the tensioning device. 65

Figure 3 is a fragmentary view taken at a right angle to Figure 2.

Figure 4 is a sectional view on line 4—4 of Figure 2.

Figure 5 is a sectional view on line 5—5 70 of Figure 3.

Referring to the drawings in detail 10 indicates a base, from which rises an adjustable standard. This standard is preferably made up of telescopic sections 11 and 12 75 respectively, the latter being of channel-like formation to receive the section 11. The section 12 is held fixed with relation to the section 11 by means of a thumb screw 13. The tensioning device in its entirety 80 is supported upon the standard, and will be hereinafter more fully described. Also carried by the standard directly beneath the tensioning device is a clamping jaw 14 which cooperates with the section 12 of the 85 standard, and is held in clamping relation therewith by means of a threaded element 15. While the thread to be dealt with may be taken from a ball, skein or the like, I have shown the invention used in connection 90 with a bobbin 16, and have provided a support for this bobbin in the nature of a shelf 17 from which rises a spindle 18 to accommodate and support the bobbin in the manner illustrated. The bobbin 16 is arranged 95 vertically, or in parallelism with the standard above described, while the shelf 17 is capable of sliding movement through an opening in the base 10, whereby the bobbin can be adjusted laterally with relation to the standard as the occasion may require.

The channel-like member includes a front wall 19, a rear wall 20, the latter rising a considerable distance above the upper edge of the front wall 19, and one end wall 21. 105 Projecting rearwardly from the wall 20 is a flange 22 which is recessed or cut away for a portion of its length as at 23, and slidably mounted in this cut away portion is an extension 24 projecting from one edge of the 110

thread engaging element 25, which constitutes the other end wall of the channel-like member 18. This tensioning element 25 is adapted to be adjusted with relation to the 5 bottom of the channel-like member, to prevent whipping of the thread or the like passing through said member. For this purpose I make use of an adjusting screw 26 upon which the extension 24 is adapted 10 to slide incident to the rotation of said screw 26, while a coil spring 27 is positioned between the extension 24 and the bottom of the channel-like member to exert a pressure on said extension and thereby assist in adjusting the element 25. The end wall 21 is provided with a thread receiving slot 28, and the thread enters this slot as it leaves the bobbin in the manner illustrated in Figure 1. The thread passes along the bottom 15 20 of the channel-like member and beneath the adjustable spring pressed tensioning element 25, which prevents whipping of the thread as will be readily understood. The thread enters the channel-like member 18 in a free 25 and unobstructed manner, that is to say that the thread is free to be drawn from the bobbin or the like from which it is taken.

In order to tension the thread while it is passing through the device, I provide a 30 weighted hammer-like member 29 which has one side beveled as at 30 and its lower edge rounded as at 31. Arranged transversely of the bottom of the channel-like member is a flange 32, and this hammer-like member 35 operates in the compartment defined by this flange and the element 25, which structure is clearly illustrated in Figure 5. The flange 32 is further provided with a thread receiving slot 33 arranged in aline with the 40 slot 28 in the end wall 21. The hammer-like member 29 is supported on one end of an angular-shaped rod 34 which is pivotally mounted on the rear wall 20 of the channel-like member 18, one end of the rod being 45 extended through an opening in the wall in a manner whereby the rod is mounted for pivotal movement. Connected in any suitable manner with the pivoted end of the rod 34, and arranged at the opposite side of the 50 wall 20, from that occupied by the rod 34 is an arm 35 which terminates in an offset end portion 36 which supports a bar 37 arranged beneath and substantially parallel with the arm 35, and which bar supports 55 a sliding weight 38 which can be held fixed in any given position upon the bar by means of a thumb nut 39. By reason of this construction, the rod 34, arm 35 and bar 37 are all mounted for pivotal movement as a unit 60 upon the rear wall 20 of the channel-like member, and manifestly by adjusting the weight 38 along the bar 37, the tension exerted by the hammer-like member 29 upon the thread as it passes through the channel-like member can be conveniently regulated,

depending of course upon the character of the thread, worsted or the like being dealt with.

Upon an inspection of Figure 5 it will be noted that the lower edge of the hammer is 70 adapted to strike the adjacent edge of a strip of relatively soft material 40, such as felt or the like which is held in the position shown by means of a clamp 41. It will be further observed that the bottom of the channel-like member is provided with an opening 42 directly beneath the hammer-like member 29 so that should lint or any other material accumulate within the channel-like member, it can readily find its way through the opening 42, thus keeping the channel-like member free from such material which would otherwise tend to clog the passage therethrough.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

1. A device of the character described comprising a base, a standard rising therefrom, 95 a channel-like member supported on said standard, and an adjustable thread tensioning element associated with said member and beneath which the thread passes for the purpose specified.

2. A device of the character described comprising a base, a standard rising therefrom, a channel-like thread receiving member supported on the standard, a bobbin support 105 slidably associated with the base, and an adjustable spring pressed thread engaging element associated with said member and beneath which the thread is adapted to pass for the purpose specified.

3. A device of the character described comprising a channel-like thread receiving member, an adjustable spring pressed thread engaging element arranged at one end of the member and beneath which the thread is adapted to pass, and means operating within 115 said member to tension the thread and to guide the latter beneath said element.

4. A device of the character described comprising a channel-like thread receiving member, an adjustable thread engaging element arranged at one end of said member and beneath which the thread is adapted to be passed, and means operating within said member to tension the thread and to guide the latter beneath said element, and said member having an opening located directly beneath said means, through which lint or other foreign matter is adapted to pass, and thereby maintain the member free from 125 obstructions.

5. A device of the character described comprising a channel-like thread receiving member, an adjustable spring pressed thread engaging element arranged at one end of the member and beneath which the thread is adapted to pass to prevent whipping of, a 10 weighted member disposed directly in advance of said element and mounted for movement toward and away from the bottom of said member, and adapted to engage the thread to tension the latter and to guide the thread beneath said element, and means for adjusting the weighted member to regulate its tension on the thread.

15 6. A device of the character described comprising a channel-like thread receiving mem-

ber, an adjustable thread engaging element arranged at one end of the member and beneath which the thread is adapted to pass to prevent whipping of the thread, a rod 20 journaled on said member, a weighted member carried by one end of the rod and operating in the channel-like member directly in advance of said element, and beneath which the thread is adapted to pass to tension the latter and to guide the thread beneath said 25 tensioning element, and an adjustable weight on the other end of said rod to vary or regulate the pressure of said weighted member on the thread.

In testimony whereof I affix my signature.
ZEDDIE LEE HARBIN.
